UNITED STATES PATENT OFFICE.

BENJMAN T. ALLISON AND JAMES J. BROWN, OF PINE BLUFF, ARKANSAS.

DESIGN FOR A TRUSS-SUPPORT.

SPECIFICATION forming part of Design No. 34,546, dated May 21, 1901.

Application filed March 29, 1901. Serial No. 53,567. Term of patent 7 years.

To all whom it may concern:

Be it known that we, BENJMAN T. ALLISON and JAMES J. BROWN, citizens of the United States, residing at Pine Bluff, in the county of Jefferson and State of Arkansas, have invented and produced a new and original Design for Truss-Supports for Supporting Truss-Rods Used on Railway-Coaches; and we do hereby declare the following to be a full, clear, and exact description of the same, reference being had to the accompanying drawings, forming a part thereof.

Figure 1 is a face view of our truss-support, showing our design. Fig. 2 is a sectional view taken on the line X X of Fig. 1.

As shown in the drawings, the leading or material feature of our design consists of a slab *a*, straight on its upper face, the slab being the same width at each end, the lower edge *b* of the slab running downwardly nearly to a point at the center of the slab. The slab is strengthened lengthwise and crosswise by an enlargement or molding *c*, running around the entire outer edges and ends of the slab.

At each end and upper edge of the slab and integral therewith are strengthening-blocks *d*, having flanges *e*, that extend rearwardly. At the center of the slab and projecting for-

wardly is a flange *f*, turning up at each end, forming upwardly-extending flanges *f'*, and 30 extending from the molding *c* are two braces *g*. The braces *g* and flange *f* are provided with concentric perforations *h*.

Running down from the flange *f* and on the front face of the slab is a brace *i*, its upper 35 end resting up against the lower face of the flange *f* and its lower end resting against the lower molding *c*. Secured in the lower end of this brace *i* is a truss-rod holder *j*.

Running horizontally through each end of 40 the slab are perforations *k*, and not far from the center of the slab, and on each side of the brace *i*, are two horizontal perforations *l*.

Having described our invention, what we claim as new, and desire to secure by Letters 45 Parent, is—

The design for a truss-support, as herein shown and described.

In testimony whereof we affix our signatures in presence of two witnesses.

BENJMAN T. ALLISON.
JAMES J. BROWN.
